GRAVITY HOSE-CO尤PLING.

1,245,332.

Specification of Letters Patent.

Patented Nov. 6, 1917.

Application filed June 24, 1903. Serial No. 162,898.

To all whom it may concern:

Be it known that I, EDWARD E. GOLD, a citizen of the United States, residing in the borough of Manhattan, city, county, and 5 State of New York, have invented certain new and useful Improvements in Gravity Hose-Couplings, of which the following is a specification.

This invention relates to direct port or 10 straight port couplers especially adapted for coupling the steam hose of railway cars. Couplers of this type are characterized by a direct or substantially straight steam passage longitudinally through the coupling 15 heads, the meeting faces of which are in a normally vertical plane substantially perpendicular to the general direction of the hose or pipe; the coupling heads are adapted to lock together by gravity, so that they 20 couple by a downward movement and are uncoupled by an upward movement; to this end such couplers have on one side of each head a locking projection or lug, and on the opposite side an arm which projects longitudinally alongside of the opposite head and 25 terminates in an inturned lug or hook having an undercut locking or wedging face adapted to engage with the projection on the opposite head. These features of construction are well understood, and couplers of 30 this character are now in almost universal use for connecting the steam heating hose of railway cars. They are applicable also for air-brake and air-signal hose connections.

35 With such direct port gravity couplers, the stability of the engagement of the respective heads when locked together is due partly to the weight of the heads which by their tendency to descend act to crowd the 40 locking provisions into closer engagement, and partly to the friction of the locking faces which engage with a wedging movement. The drawing apart of the cars when uncoupled acts to straighten the hose and 45 thereby to throw up the couplers, and automatically uncouples them. This automatic uncoupling is assured by forming the necks on the coupling heads for the attachment of the hose thereto, to project upward at such 50 an angle that the straightening out of the hose will tilt up the seating faces and there-

by disengage the coupling provisions. It is practically necessary to make the couplers capable of automatic uncoupling, so that if, in uncoupling two cars, the trainman should 55 omit to part the hose coupling, the latter may part itself by the straightening out of the hose, and without injury to the latter. In the endeavor to maintain the capacity for automatic uncoupling, it has been heretofore 60 found impossible to provide against the occasional pulling apart of the couplers on exceptionally sharp curves, and especially on reverse curves. The margin between the straightening of the hose on such a curve 65 and such straightening of the hose as should effect automatic uncoupling, is a narrow one. Accidental uncoupling is also frequently caused by the couplers hanging too low and striking a frog or switch, which throws the 70 couplers up.

It is the object of my invention to supplement the ordinary gravity locking provisions with such additional and auxiliary fastening means as will practically insure 75 against the accidental uncoupling of the couplers on reverse curves, or under any other conditions where their uncoupling is to be avoided, without preventing their normal automatic uncoupling when the uncoupled cars are drawn apart. My invention also aims to avoid introducing any difficulty in the manual coupling or uncoupling operations, but on the contrary to facilitate the coupling operation by the provision of means 80 for assisting in guiding the respective heads correctly together in the act of coupling. To these ends my invention provides in combination with the ordinary locking provisions of a direct port gravity coupler, an 85 additional or supplemental impositive locking provision consisting of a spring-actuated latch on one coupling head adapted to engage a recess or reciprocal face on the other coupling head, so as to resist but not prevent 90 the uncoupling movement. The resistance thus imparted is added to the effect of gravity and friction upon the ordinary coupling provisions, and is so graduated as to increase 95 the reluctance to uncoupling to an extent 100 sufficient to prevent the accidental parting of the heads without interfering with their

normal automatic uncoupling. The spring latch may be variously formed, and the spring pressure may be variously applied to it; likewise the recess or engaging face on the 5 opposite coupler with which it coacts may be variously shaped, provided their interrelation be such as to attain the effect of co-operating to the desired degree with the actuation of the gravity locking provisions. Thus 10 either or both of the interengaging faces may be inclined, so as to introduce a wedging action, or in any other way may the latch be made to resist the uncoupling movement by a flexure of its spring. To attain 15 symmetry, I prefer to provide each coupling head with a spring latch, and with a recess or engaging face to coact with the latch on the opposite head.

The nature of my invention being now 20 understood, I will proceed to describe in detail its preferred embodiment with reference to the accompanying drawings, wherein—

Figure 1 is a bottom view of a pair of 25 Gold straight port couplers intercoupled, showing the application of my invention thereto, the respective couplers being partly broken away and in section on the oblique plane 1—1 of Fig. 2;

30 Figs. 2 and 3 are side views of the respective coupling heads separated, showing my invention as applied thereto;

Fig. 4 is a vertical transverse section in 35 three planes denoted approximately by the dotted line 4—4 in Fig. 1;

Fig. 5 is a fragmentary oblique section on the line 5—5 in Fig. 3.

Referring to the drawings, let A A designate the respective coupling heads, each of 40 which is provided as usual with a tubular upturned neck B for the attachment of the hose, a seat or gasket C for making a steam-tight joint with the abutting head, and with the usual locking provisions comprising a 45 locking projection D (Fig. 3) on one side, called the "lug," and a forwardly projecting locking arm E on the other side having an inturned lug or locking projection F, called the "hook." The engaging faces of 50 the projections D and F are made to overhang so as to hook together, as indicated in Fig. 1. In the Gold couplers, each head is also provided with a boss G on one side having a threaded hole into which to screw a 55 drainage trap. All of the parts thus far referred to, and their operation in coupling and uncoupling, are so well understood that further description is unnecessary.

60 My present invention adds to each coupler a spring latch, comprising in its preferred construction a spring-pressed bolt or pin H, which acts against a suitable engaging face on the opposite head, preferably a recess I.

The latch presses in such direction, and is so formed where it engages the face I, and 65 the latter is so shaped or inclined that their mutual engagement acts to resist the uncoupling movement of the respective heads;

that is to say, their tendency is to prevent the upward and out-swinging movement of 70 the heads necessary to uncouple, their resistance to this movement being sufficient to prevent accidental uncoupling but not sufficient to prevent the normal automatic uncoupling.

Obviously this result may be obtained by various arrangements and shapes of the latch H and face I, but for practical 75 purposes the shapes, locations and relative arrangements shown are found preferable.

Accordingly I will proceed to describe in 80 detail the specific construction shown. The latch H is in the form of a cylindrical bolt or pin passing horizontally through the locking arm E and preferably through its thickened part forming the hook F, and projecting beyond this portion sufficiently to enter into the recess I which is formed in a corresponding location on the side of the opposite head. While the spring pressure 85 may be variously applied, I have found it preferable to construct the spring as a leaf-spring K, fastened rigidly to or formed integrally with the pin, and extending along the locking arm E on the outer side thereof, and fastened at its opposite end to the coupling head, preferably by a rivet a, although 90 any other suitable fastening may be employed. I find it preferable to arrange the spring on the exterior side of the arm, and in order to secure as great a length of spring 95 as possible, to extend it obliquely, as shown in Fig. 2. This arrangement locates the pin H toward the upper side of the locking arm, 100 where it is most effective, and carries the rivet or fastening a to the lower side thereof 105 where it is beneath the boss G. To both guide and protect the spring, the outer side of the arm is formed preferably with oblique ribs b b between which the spring lies.

As shown the recess I is shaped to present 110 on engagement with the latch when the coupling is locked, an oblique face, as clearly shown in Fig. 4, the effect of which is to tend to force the latch lower and thereby draw the locking arm into closer engagement, but this is not essential. Sufficient play is afforded by the extension of the recess I on its lower side at c beyond the normal position of the latch H, to allow for an abnormal engagement of the heads such as 115 occurs when the gaskets C C become worn or their packing rings are unusually compressed. Thus when the coupling heads are locked as shown in Fig. 1, the springs K K are pressed outward as indicated. When 120 uncoupled the springs press in and lie flat 125

against the outer faces of the arms. To facilitate coupling, the approach to the recess is formed as a groove J having a gradual incline, best shown in Fig. 5. This groove is 5 arc shaped, and its outer and inner sides (chiefly the latter) serve to guide the latch in its correct approach to the recess I. The engaging end of the latch H may be rounded as shown, or otherwise beveled or wedge 10 shaped, the groove J being correspondingly shaped to properly engage with and guide the latch. When both coupling heads are formed with grooves J and provided with latches H, the engagement of these parts 15 serves as an assistance to the trainman in uniting the couplers, since they facilitate the initial fitting of the heads together in their upright position, and their subsequent down-swinging movement in correct relation to 20 properly couple them, and serve to bring the seats into alinement and hold them there.

My invention contemplates the provision of a spring latch on one head and a recess or other engaging face to coact with it on 25 the other head, but preferably both heads will be provided with both the latch and recess, not only for symmetry, but to enable any head to inter-couple with any other head. The former arrangement, however, 30 where the couplers are respectively rights and lefts, may be used on roads where cars are never turned end for end, but always couple in the same relation.

Practical use of my invention has demonstrated that the spring latch so effectively co-operates with and reinforces the coupling action of the gravity coupling provisions, that accidental uncoupling, even on the sharpest reverse curves used in practice, is 35 wholly prevented, without impairing the capacity of the coupler for automatic uncoupling in the event that the trainman shall have forgotten to uncouple the hose. The addition of the spring latch serves to facilitate the coupling action, rendering the correct approach of the respective heads more certain and easy. In uncoupling, the latch easily responds to the manual uptilting movement which is essential to uncoupling, 40 and requires only that this movement be started by a somewhat sharper pull than is commonly given in uncoupling couplers of this type.

To enable the bolt H to resist the lateral or tilting strain to which it is subjected by its pressure against the inclined face I and prevent the transmission of this strain to the spring, the bolt H is preferably supported at its inner and outer ends in the 45 manner best shown in Fig. 4. The hole in the arm through which the bolt passes is caused to approach closely beneath it toward its inner end at e, and closely over it

near its outer end at f. Thus under strain the bolt H serves as a lever supported at the 65 opposite points e f. When the bolt is as shown formed integrally with the spring K, the stiffness of their connection makes it desirable that the hole shall be elongated as shown in Fig. 3, so that as the bolt is 70 pressed back by the rising incline J, it has enough room to swing outwardly.

I am well aware that it has frequently been proposed to construct hose or pipe couplings with coupling provisions in the nature of a spring latch or lock for uniting the respective coupling heads, but in all such cases the spring latch has either been the sole means for holding the heads united, or has been an essential adjunct of other means, 75 such for example as a screw or bayonet joint, and in all such couplings the coupling has been effected either by a rotary movement around the axis of the meeting faces, or by a sliding engagement parallel with such 80 axis, or by a rocking movement on a transverse axis, the spring latch being essential to hold the heads coupled. Prior to my invention a spring latch has not so far as I am aware been applied as an auxiliary locking device to a gravity coupler where the 85 heads are primarily locked together by interengaging locking faces locking by a gravity action and unlocking in opposition to the action of gravity. 90

It will be understood that the guiding function of the grooves J having arc-shaped inner or outer faces and co-operating with the engaging ends of the latches or bolts H, is independent of the yielding or spring-latch function of the bolts; that is to say, the rising and falling inclines forming the bottoms of the grooves J and recesses I and which serve to impart endwise movement to the spring-pressed latches or bolts, are 100 the only parts of the grooves and recesses which co-operate with the spring-latch function of the bolts, the guiding function of the grooves being performed by their arc-shaped inner or outer faces or both engaging the inner or outer sides of the bolts H and thereby, independently of any endwise movement of the bolts, serving to guide the coupling heads in their descending or coupling movement and serving to bring their 105 gravity locking provisions (namely, the projections D and F) into correct engagement, and to bring their seats or gaskets into alinement, and after coupling to hold them 110 in such alinement. 115

What I claim is:—

1. A direct-port gravity hose-coupler for railway cars, comprising reciprocally-engaging heads having locking means comprising a lug on one side of each head and an 125 arm on the opposite side formed with a hook.

- for engaging the lug on the other head, adapted to couple by a downward swinging movement, to hold the heads coupled against internal pressure during normal running, 5 and to uncouple automatically with an upward movement by the tautening of the hose as the cars draw apart, the one head provided with an auxiliary spring latch and the other head having a recess adapted to 10 receive such latch, the latch and recess being relatively formed to engage impositively, and when engaged adapted to resist the uncoupling movement to prevent accidental uncoupling.
- 15 2. A direct-port gravity hose-coupler having on one side of its head a locking lug and on the other side a hooked locking arm, adapted to engage such lug on a mating coupler, adapted to couple with its mating 20 coupler by a downward swinging movement and to automatically uncouple with an upward movement by the tautening of the hose as the cars draw apart, and having a recess in the side of its head, adapted to receive 25 an impositive spring latch projecting horizontally through the arm of the mating coupler.
3. A direct-port gravity hose-coupler having on one side of its head a locking lug and 30 on the other side a hooked locking arm adapted to engage such lug on a mating coupler, and having a recess in the side of its head, adapted to receive a spring latch projecting from the mating coupler, and an 35 incline adapted to press back such latch during the coupling movement.
4. A direct-port gravity hose-coupler having on one side of its head a locking lug and on the other side a hooked locking arm 40 adapted to engage such lug on a mating coupler, and having a recess adapted to receive a spring latch on the mating coupler and a groove adapted to guide said latch into said recess.
- 45 5. A direct-port gravity hose-coupler having on one side of its head a locking lug and on the other side a hooked locking arm adapted to engage such lug on a mating coupler, combined with a spring latch adapted 50 to engage the mating coupler, and with an arc-shaped guiding face adapted to receive a latch on the mating coupler and guide it during the coupling movement.
6. A direct-port gravity hose-coupler having locking means comprising a lug on one 55 side of its head and on the other side a hooked locking arm adapted to engage such lug on a mating coupler, combined with an auxiliary impositive spring latch comprising a pin passing through an opening in said 60 arm, and adapted to impositively engage the side of the mating coupler, and in coöperation with said locking means to resist the

uncoupling movement sufficiently to prevent accidental uncoupling, but not sufficiently to 65 prevent automatic uncoupling as the cars draw apart.

7. A direct-port gravity hose-coupler having locking means comprising a lug on one side of its head and on the other side a 70 hooked locking arm adapted to engage such lug on a mating coupler, combined with an auxiliary impositive spring latch comprising a pin passing through an opening in said arm, and a leaf spring engaging the 75 outer end of said pin, extended along the outer side of said arm, and fastened thereto, said latch adapted in coöperation with said locking means to resist the uncoupling movement sufficiently to prevent accidental uncoupling, but not sufficiently to prevent automatic uncoupling as the cars draw apart.

8. A direct-port gravity hose-coupler having locking means comprising a lug on one side of its head and on the other side a 80 hooked locking arm adapted to engage such lug on a mating coupler, combined with an auxiliary impositive spring latch comprising a pin passing through an opening in said arm, and a leaf spring united integrally 85 to said pin, extended along the exterior of the arm, and fastened thereto, said latch adapted in coöperation with said locking means to resist the uncoupling movement sufficiently to prevent accidental uncoupling, 90 but not sufficiently to prevent automatic uncoupling as the cars draw apart.

9. A direct-port gravity hose-coupler having locking means comprising a lug on one side of its head and on the other side a 100 hooked locking arm adapted to engage such lug on a mating coupler, combined with an auxiliary impositive spring latch comprising a pin passing through an opening in said arm, and a leaf spring engaging the 105 outer end of said pin, extended along the outer end of said arm, and fastened thereto, said arm formed with longitudinal ribs parallel with and protecting said spring, said latch adapted in coöperation with said locking means to resist the uncoupling movement sufficiently to prevent accidental uncoupling, but not sufficiently to prevent automatic uncoupling as the cars draw apart.

10. A direct-port gravity hose-coupler having on one side of its head a locking lug and on the other side a hooked locking arm adapted to engage such lug on a mating coupler, combined with an auxiliary impositive spring latch comprising a pin passing through an opening in said arm, above the middle thereof, and a leaf spring engaging said pin, extended obliquely along the outer side of said arm, and fastened there-to at a point below its middle.

11. A direct-port gravity hose-coupler

having on one side of its head a locking lug and on the other side a hooked locking arm adapted to engage such lug on a mating coupler, combined with an auxiliary im-
5 positive spring latch comprising a pin passing through an opening in said arm, and a leaf spring engaging the outer end of said pin, extended along the outer side of said arm, and fastened thereto, and said arm
10 having an elongated opening with bearing

shoulders *e f* on opposite sides to support said pin.

In witness whereof, I have hereunto signed my name in the presence of two sub-
scribing witnesses.

EDWARD E. GOLD.
